HOUSING FOR AN OUTBOARD PROPULSION UNIT

Robert T. Johnson, Arthur F. Miller, and Richard H. Schwab, Oshkosh, Wis., assignors to Brunswick Corporation, Chicago, Ill., a corporation of Delaware

Filed Aug. 26, 1968, Ser. No. 13,273

Term of patent 14 years

Int. Cl. D12—06

U.S. Cl. D71—1

FIG. 1

FIG. 2

FIG. 3

FIG. 4

FIGURE 1 is a side elevation of a housing for an outboard propulsion unit, showing our new design, the opposite side being a mirror image thereof;

FIG. 2 is a front elevation of the housing, taken from the left of FIGURE 1;

FIG. 3 is a rear elevation of the housing, taken from the right of FIGURE 1; and

FIG. 4 is a bottom plan view thereof.

The dominant features of our design reside in the portions shown in full lines.

We claim:

The ornamental design for a housing for an outboard propulsion unit, substantially as shown and described.
